GRINDING IMPLEMENT FOR ARTICLES OF
HARD MATERIAL

Reuben H. Hood, Durango, Colo.

Application September 21, 1945, Serial No. 617,751

3 Claims. (Cl. 51—309)

My invention relates to a grinding implement or so called "cone-lap" used in grinding, shaping and polishing hard-faced articles, such as stone, glass, diamonds and other gems as well as hard metal and porcelain, in other words, a lapidary tool.

This "cone-lap" which is preferably made of cast iron in one piece, has the form of a hollow cone or cup-shaped member, with a shank for securing it to a spinning shaft or arbor revolvable in both directions.

The preferred construction of this implement or "cone-lap" is illustrated in the accompanying drawing wherein:

Figure 1 is a top plan view of the implement, and

Figure 2 is an axial section along line 2—2 of Figure 1.

This tool, as already stated and as here shown is a one-piece, iron casting and has a narrow shank 10 adapted for securing by means of a set screw 11 on the end of a vertical shaft or arbor which is revolvable either in right hand or left hand direction.

Besides its shank 10 having the bore 19, the tool consists of a middle or tapered portion 12 and an outer or table portion 13 all made in one continuous casting with thick walls so as to resist breaking at high speed of rotation.

The walls of the tapered portion 12 of the tool merge on the outside at the smaller end with the shank 10 and then taper uniformly upwards as far as the abrupt shoulder 14 with well-rounded corners forming the bottom part of the table portion or head 13. The top or head of the table portion 13 has a flat, horizontal surface 22 running at right angles to the axis of the tool.

The cavity of the tool consists of a depression 15 about one inch deep with a flat bottom 16 and inclined side surfaces 17 at an angle of about 18° against the vertical.

Coaxial with the depression 15 in the tool a central cavity 18 is formed in the shape of an inverted cone with its base in the bottom 16 of the depression 15 having a taper of about 36° and terminating short of the bore 19 in the shank 10, but it does not connect therewith. The corners where the sides 20 of the cavity 18 merge with the bottom 16 are well rounded, but the corners at the top and bottom surfaces 22 and 16 of the depression 15 are preferably sharp.

Suitable dimensions for a tool of this character are about five and one-half inches overall length, about five and one-quarter inches, largest diameter of head 13, and one and one-half outside

diameter of shank 10, with walls 12 of uniform thickness about three-quarters of an inch.

The operation of this tool is the following: the article to be shaped, ground or polished is cemented to a rod or wooden handle (so-called "lap stick"). As cementing material wax may be used. This rod is held firmly in one hand, the "cone-lap" is then started to revolve with an abrasive covering the surfaces of its cavity and the stick with the article attached held in the cavity.

If the article is to have a circular shape, the article is then pushed down into the inner cavity 18.

In order to grind the article to produce an oval, convex shape, the rod with the article is held tilted in the "cone-lap" and one side ground on one side against one side of the cavity 18 and the other side of the article ground on the 20 opposite side of cavity 18.

To produce a concave grind the article is pressed against the rounded edge 20. In order to grind flat surfaces on objects with square, rectangular, hexagonal and triangular shapes, 25 the same is pressed against the flat bottom 16 of depression 15.

Finally for grinding the crown of a gear the rod is held at an angle of about 20° with the face of the gear against the side surface 17 30 of the depression 15.

Many designs and shapes may be obtained by combining the here enumerated methods. All gems and stones ground on this "cone-lap" have the proper basic angles.

35 By the use of the same all grinding is speeded up, more accurate work obtained and less power required than with any now known methods and implements.

It is to be understood that many changes may 40 be made in details and shape as well as material within the scope of the subjoined claims.

I claim:

1. A grinding implement for gems and similar hard-faced articles, consisting of a forwardly 45 tapering head with a shank adapted for attaching to a rapidly revolving shaft and provided with a cavity of graduated, stepped cones arranged with a large truncated cone forward.

2. A grinding implement for gems and similar 50 hard-faced articles, consisting of a forwardly tapering head with a shank adapted for attaching to a rapidly revolving shaft and provided with a cavity of graduated, stepped cones arranged with a large truncated cone forward, the 55 truncated cone having a flat bottom with a dimin-

ished circular opening forming the base of a second cone terminating with its apex adjacent said shank.

3. A grinding implement for gems and similar hard-faced articles consisting of a cast iron body having a shank for attaching to a rapidly revolving shaft, an intermediary portion increasing gradually in diameter from said shank, said body terminating with an enlarged head portion forming a shoulder with said intermediary portion, a cavity in said body provided with circumferen-

tial and transversal grinding surfaces having rounded edges at their juncture, the surfaces of said cavity forming an outer truncated cone and an inner cone joined by said transverse grinding surface, the base of the inner cone providing a central opening with well-rounded edge in the transverse surface and having its apex adjacent said shank, both cones being coaxial in said body.
